UNITED STATES PATENT OFFICE.

MACDONALD S. REED, OF ERIE, PENNSYLVANIA, ASSIGNOR TO ERIE FOUNDRY COMPANY, OF ERIE, PENNSYLVANIA, A CORPORATION OF PENNSYLVANIA.

POWER HAMMER.

Application filed November 12, 1924. Serial No. 749,477.

This invention is designed to improve board drop hammers. The friction rollers of such hammers have heretofore been driven by gears but in such instances the gears have 5 ordinarily had their relation varied as the rollers were adjusted to and from the board. In the present invention I maintain the pitch relation of the gears constant. It is desirable with heavy duty hammers to supply 10 a plurality of pairs of friction rollers so that the pressure on the board may be distributed. In the present invention this is accomplished and at the same time the rolls of the two pairs are mounted on eveners so that the 15 frictional engagement of both pairs of rolls is equal. Details and features of the invention will further appear from the specification and claims.

The invention is illustrated in the accompanying drawings as follows:

Fig. 1 shows a front elevation of a drop hammer.

Fig. 2 a section on the line 2—2 in Fig. 3.

Fig. 3 a side elevation of the roll mechanism of the drop hammer, parts being broken away to better show construction.

1 marks the anvil, 2 the frame, 3 the sow block, 4 the ram, 5 the guides in the frame 30 for the ram, and 6 the boards secured to the ram in the usual manner. A cap 2^a is arranged at the top of the frame and forms the frame for the friction rolls. The friction rolls are arranged in pairs, the rolls 7 and 9 forming the top pair and the rolls 8 and 10 the lower pair. The rolls 9 and 10 are mounted on eveners 11. These eveners are journaled on an oscillating mounting 12 eccentrically mounted in bearings 13 in the 35 cap 2^a. By swinging the eccentric or mounting 12 the eveners 11 carrying the rolls 9 and 10 are moved to and from the board. The rolls 9 and 10 are carried by shafts 9^a and 10^a journaled in the ends of the eveners.

45 The rolls 7 and 8 are mounted on shafts 7^a and 8^a and these shafts are journaled in eveners 14 similar to the eveners 11 and the eveners 14 are mounted on an eccentric mounting 15, the mounting being journaled in bearings 15^a in the frame. The eccentric 50 12 has an arm 16 by means of which the rolls 9 and 10 are moved toward and from the board. An operating rod 17 is secured to the arm 16 and is operated by the lift 55 lever 18 for disengaging the rolls and is

released or dropped by a latch 19 in the usual manner when the hammer reaches its lower position. These parts operate in the usual manner of hammers of this type and are well understood.

An arm 20 extends from the eccentric 15 and has an adjusting mechanism (not shown) secured to an eye 21 so that it may be adjusted for wear. Otherwise this eccentric remains stationary in the ordinary operation of the machine.

A drive wheel 22 is mounted on a shaft 23. The shaft 23 extends through and is journaled in the eccentric 12 and is concentric with the eveners 11. A gear 24 is fixed 70 on the shaft 23 at the opposite end from the wheel 22 and meshes with gears 25 and 26 on the shafts 9^a and 10^a respectively. In this way the rolls 9 and 10 are gear driven and it will be noted that inasmuch as the shafts 9^a and 10^a remain in constant relation to the shaft 23 the pitch relation of the gears remain constant. A drive pulley 27 is mounted on a shaft 28 mounted in the eccentric 15 in a manner similar to the shaft 75 23 and is concentric to the eveners 14. A gear 29 shown in dotted lines in Fig. 3 is fixed on the shaft 28 and meshes with gears 30 and 31 on the shafts 7^a and 8^a. In this way the friction rolls 7 and 8 are gear-driven and in this gear connection as in the one involving the gears 24, 25 and 26, the pitch relation remains constant.

With this structure through the action of the eveners equal pressure is delivered to 90 the board at different points in the movement of the board even though the board in service may become somewhat varying in thickness and this result is accomplished without in any way disturbing the even 95 driving of the rolls.

What I claim as new is:

1. In a power hammer, the combination 100 of an operating board; two movable actuating friction rolls; shafts on which said movable friction rolls are mounted; two rolls opposing the movable rolls; an evener in which said shafts are journaled; an eccentric on which the evener is mounted; a drive shaft mounted in the eccentric, said drive shaft being concentric with the evener; and gears on said shafts, said gears being in driving relation.

2. In a power hammer, the combination 110 of an operating board; a set of two movable

- rolls at one side of the board; a set of two opposing rolls at the opposite side of the board; an evener on which the movable rolls are mounted comprising a swinging frame having its axis in a plane at right angles to the board and between the movable rolls; means moving the evener bodily to move the movable rolls; and means for driving one of said rolls.
10. 3. In a power hammer, the combination of an operating board; a set of two movable rolls at one side of the board; a set of two opposing rolls at the opposite side of the board; an evener on which the movable rolls are mounted comprising a swinging frame having its axis in a plane at right angles to the board and between the movable rolls; an eccentric on which the evener is mounted; means actuating the eccentric to move the evener and with the evener the rolls toward and from the board; and means actuating one of the rolls.
15. 4. In a power hammer, the combination of an operating board; a set of two actuating movable friction rolls at one side of the board; a set of two opposing rolls mounted at the opposite side of the board; an evener on which the movable rolls are mounted comprising a swinging frame having its axis in a plane at right angles to the board and between the movable rolls; means moving the evener bodily to move the movable rolls into engagement with the board; and means driving the actuating rolls.
20. 5. In a power hammer, the combination of an operating board; a set of two actuating movable friction rolls at one side of the board; a set of two opposing rolls mounted at the opposite side of the board; an evener on which the movable rolls are mounted comprising a swinging frame having its axis in a plane at right angles to the board and between the movable rolls; means moving the evener bodily to move the movable rolls into engagement with the board; and means driving the actuating rolls.
25. 6. In a power hammer, the combination of an operating board; two sets of two friction rolls at each side of the board; eveners on which the rolls of each set are mounted, each evener comprising a swinging frame having its axis in a plane at right angles to the board and between the rolls mounted thereon; and means driving the actuating rolls comprising a gear system having a gear concentric with the evener and a gear on an actuating roll.
30. 7. In a power hammer, the combination of an operating board; two sets of two friction rolls at each side of the board; eveners on which the rolls of each set are mounted, each evener comprising a swinging frame having its axis in a plane at right angles to the board and between the rolls mounted thereon; and means for moving the eveners toward and from the board.
35. 8. In a power hammer, the combination of an operating board; two sets of two friction rolls at each side of the board; two eveners, one for each set of rolls on which said sets are mounted, each evener comprising a swinging frame having its axis in a plane at right angles to the board and between the rolls carried by the frame; means for moving the eveners toward and from the board; and gear driving mechanisms for said rolls having driving gears concentric with the axis of the eveners meshing with gears concentric with the rolls.
40. In testimony whereof I have hereunto set my hand.

MACDONALD S. REED.
